United States Patent Office.

STEPHEN FOUNTAIN, OF SILVER CITY, NEVADA.

Letters Patent No. 77,183, dated April 28, 1868.

IMPROVED AMALGAMATOR.

The Schedule referred to in these Letters Patent and making part of the same.

TO ALL WHOM IT MAY CONCERN:

Be it known that I, STEPHEN FOUNTAIN, of Silver City, county of Lyon, State of Nevada, have invented an Improved Amalgamator for saving the precious metals; and I do hereby declare the following description and accompanying drawings are sufficient to enable any person skilled in the art or science to which it most nearly appertains to make and use my said invention or improvement without further invention or experiment.

The nature of my invention consists in providing an amalgamating-pan with a steam-chamber around its centre, to be cast entire, and of one piece with the pan, which materially lessens the cost of construction, and avoids liability to leakage.

To describe my improvement, I refer to the accompanying drawing forming part of this specification, of which—

Figure 1 is a plan of my improved pan,

Figure 2 is a sectional elevation of the amalgamator, and

Figure 3 a bottom view of the muller.

I cast my pan, A, which may be of such size as may be required, with a hollow hub for the shaft which operates the muller to pass through, said hub having a double wall around the opening for the shaft to form the steam-tight chamber B, as represented in fig. 2. Into this chamber I admit steam through holes in the bottom, to supply the heat required in the use of the machine. The pan, together with the aforesaid hollow chamber, with holes in the bottom for the admission of steam, may be cast in the usual manner of casting hollow ware, well known and practised by foundrymen.

Fig. 1 represents the bottom of the pan, with the iron dies C C alternating with the blocks of wood D D, and surrounded by the curved wooden pieces E E. The muller E', fig. 3, revolves around the steam-chamber B, the shoes F F, with the inclined projections G G, being attached to said muller in the usual way, by projections, slots, and keys.

What I claim as my invention and improvement in amalgamators, is—

Casting the pan with a hub, having an opening through it for the shaft to pass through, and having a double wall around this opening to form a steam-chamber for supplying heat to the machine, substantially as described.

In testimony whereof, I hereunto set my hand and seal.

STEPHEN FOUNTAIN. [L. S.]
